UNITED STATES PATENT OFFICE.

VLADIMIR B. SOUNITZA, OF NEW YORK, N. Y.

PUMPING APPARATUS.

Application filed February 17, 1925. Serial No. 9,764.

To all whom it may concern:

Be it known that I, VLADIMIR B. SOUNITZA, citizen of Russia, and resident of New York city, in the county of New York and 5 State of New York, have invented certain new and useful Improvements in Pumping Apparatus, of which the following is a specification.

My invention relates to bailing apparatus 10 and has a particular reference to apparatus adapted for bailing or pumping the oil from the wells in the production of crude oil.

The object of my invention is to provide 15 a bailing apparatus which could be easily adjusted in regard to its bailing or pumping capacity within wide limits by purely mechanical means.

In pumping out crude oil from the wells 20 it is often necessary to adjust the speed and stroke of the pump according to the rate of the natural flow of the oil. This adjustment is usually accomplished by varying the speed of the electric motor operating the pump, but in practice the variations required usually greatly exceed the maximum possible limits of the speed variations of 25 the driving motors. In my apparatus this speed variation or adjustment is accomplished by mechanical adjustments with 30 which I can change the pumping capacity of the apparatus within limits of 3:1 and even more.

My invention is more fully described in 35 the accompanying specification and drawing in which—

Fig. 1 is an elevation showing my apparatus in connection with the upper end of a casing pipe in the well and an operating mechanism, Fig. 2 is an end view of same, 40 Fig. 3 is a side view showing another position of my apparatus, Figs. 4 and 5 are sectional detailed views of parts of my apparatus, Fig. 6 is a view of the central saddle, Fig. 7 is an end hook, Figs. 8, 9 and 10 are 45 views of hinged links.

My bailing apparatus consists of a central or pumping rod 1 extending inside of a casing pipe 2 in a well and passing through an adjustable oil tight packing gland 3 on top of the pipe 2. A bracket 4 is permanently attached to the top of the pipe and 50 is provided with two clevises or forks 5. Links 6 are pivoted in the clevises 5 and are provided with pins 7 on the ends, forming pivoted connections for the ends of oval

links 8 and 9. Links 8 are made narrow and fit inside of the wider links 9. They are provided with central apertures 10 for pins 11, forming pivoted connections between them. 60

The upper ends of the links 8 and 9 are pivotally connected with the lower ends of similar links 12 and 13. The upper ends of the links 12 and 13 are pivoted to the lower ends of longer links 15 and 16 which in turn 65 are connected with short top links 17 and 18.

The combination of these links forms an expansive structure with different rate of movement at its different points.

The lower pins 11 and 14 serve only to 70 joint the links, but upper pins 19 are also adapted to support guiding brackets 20 for the rod 1 and lifting rings 21. Other pins 22 are adapted only for supporting other guiding brackets. 75

For this purpose the pins 19 are provided 75 with recesses and shoulders 23 and 24 on their inner ends. Guiding brackets 20 are provided with open slots 25 underneath with which they slide over the pin shouldered extensions. The recesses 27 of the brackets are made to fit shoulders 24 of the pins, thereby locking the pins in their positions. Central apertures 28 in the brackets provide a free passage for the rod 1. The 80 apertures expand into cup shaped receptacles 29 on top for the cone shaped lower extensions of the clamps 30. These clamps are split lengthwise and are provided with bolts 31 with which the two halves of the clamp 85 are jammed together against the rod 1 thereby securing the clamp in a desired position. 90

The weight of the rod 1 with a pump plunger at the bottom end (not shown) tend 95 to keep the bracket 20 in an engagement with the pins 22.

The pins 19 have also outer extensions 32 with shoulders 33, adapted to engage corresponding recesses in lifting rings 21. The lower aperture 34 is made sufficiently large 100 to pass the head 33 of the pin, but it is made narrower at the bottom by means of a shoulder 35 adapted to fit the recess 32, when there is an upward pull exerted on the ring 21. 105

The upper apertures 36 of the rings 21 engage eye rings 37 attached to the ends of a steel cable 38. The cable is passed over sheaves 39 journaled on pins 40 fitted in the end of a balancing arm 41. The middle por- 110

tion of the cable is passed over a central or compensating sheave or block 42, journaled on a pin 43. Curved guides 44, forming extensions of the arm 41, maintain the correct direction for the cable ends for all positions of the arm 41. This arrangement of three blocks or sheaves admits of a perfect self alignment of the cable on both sides and equalizes the tension from the pump plunger 10 and rod 1.

A spacing ring 45 is placed on the upper end of the rod 1 in order to keep the cables from rubbing against the links. This ring is not shown in Figs. 1 and 3, and in the 15 latter figure the rod 1 is also omitted.

The arm 41 is supported at the middle on a post 46, being rotatively mounted on a shaft 47. The other end of the arm is provided with a groove 48 for a hook 49 attached to the end of an oscillating rod 50. This rod has a slot with rollers 51 and 52 on pins 53, adapted to engage an eccentric 54 on a shaft 55. The shaft 55 is connected with a motor (not shown) or other source of 25 power.

The operation of my device is as follows. The rotation of the shaft 55 with the eccentric 54 causes the rod 50 to oscillate between guides 56. This oscillating movement is 30 transmitted to the rocking arm 41 which in turn exerts intermittent lifting pull on the cables 38 and, through cable connections 37 and 21, on the links 12 and 13.

The resultant oscillating motion of the 35 joint at the pin 19 is indicated on the drawing with the character "H", and the corresponding motions of the other joints above are correspondingly increased, progressing to the top of the mechanism. The upper 40 joint 57 moves accordingly through a distance n times greater, which is marked with characters " nH " on the drawing (Figs. 1 and 3).

Therefore by placing the clamp 30 above 45 any desired guide 20 it is possible to select any desired amount of travel for the rod 1 within limits of the speeds of different joints of the mechanism. Instead of replacing the same clamp 30, a plurality of clamps may be 50 provided loosely placed on the rod above the joints, or clamped in inoperative positions, only one clamp being clamped in an operative position, supporting the rod 1 at a desired joint.

Longer links 15 and 16 provide a greater 55 step between successive speeds or travels for the points 22 and 58, simplifying the construction and eliminating two extra joints, as would be the case with a double number of shorter links. Of course, a larger number of shorter links may be used in cases when a greater variety of speeds and travel distances is desired.

The reciprocating motion of the cable is 60 communicated to the rod 1, as explained

above, thereby operating the pump plunger at the lower end of the rod (not shown) and pumping the oil from the well. This oil is then exhausted through a side pipe 59 and may be directed to any suitable container. 70

When the flow of oil is rapid, the rod 1 is connected to the highest point of the mechanism, giving the pump plunger a maximum of movement and the highest rate of pumping. The power expenditure will be correspondingly large. 75

With a diminished rate of flow the rod 1 may be locked to some intermediate joint of the mechanism so as to reduce the rate of pumping and the power requirements. With 80 a properly constructed mechanism it is possible to get all the pumping speeds desired with ordinary constant speed electric motors, operating the shaft 55, thereby effecting a considerable economy in the installation. 85

The simple mechanical connections shown are made possible by the fact that all joints are under constant vertical tension from the rod 1. 90

It should be noted, that the operating mechanism may be made of any suitable construction, and, for instance, instead of an eccentric 54, a crankshaft connection may be used, or other similar device adapted to produce a reciprocating movement for the 95 rocking arm 41.

The links 8, 9, 12, 13, 15 and 16 may be constructed in any desired shape and form and in any desired number. The mechanism may be also made to operate in an inverted 100 position, that is with the point 57 fixed or stationary and with the point 14 free to move up and down.

Important advantages of my mechanism are that it permits use of wide range of 105 pumping capacities for the same arrangement and with the same driving motor; also a constant speed motor may be used with a corresponding economy in the motor itself and the control mechanism. The parts of my mechanism are simple to make, easy to assemble and can be easily taken care of by an ordinary mechanic.

Another advantage is that for different 110 strokes of the pump the motor speed may be kept constant, thereby obtaining its highest efficiency and not subjecting the reciprocating parts to greater stresses which are produced if the motor speed is increased.

In order to operate my toggle jointed system of links any suitable flexible carriers may be used, such as cables, chains, ropes, etc.

Instead of ring shaped links, as shown, a double row of flat links may be also used.

I claim as my invention:

1. In a pumping mechanism, the combination with a pump plunger, a casing pipe, a rod extending from said plunger through the top of said casing pipe, a plurality of links pivoted together and forming an ex- 130

pansive system, means to support one end of said system, means to impart a reciprocating movement to said system, and means to connect said rod with different links of said system.

2. In a pumping mechanism, the combination with a pump plunger, a casing pipe for said plunger, a rod extending from said plunger through the top of said casing pipe,

10 a plurality of ring shaped links pivoted together at their middle portions and at their ends and forming an expansive toggle jointed system, means to support one end of said system, said rod being adapted to pass inside of said ring shaped links, means to impart a reciprocating movement to said system, and means to connect said rod selectively with one of the joints of said system.

3. In a pumping mechanism, the combination with a pump plunger, a casing pipe, a rod extending from said plunger through the top of said pipe, a plurality of ring shaped links pivoted together at their middle portions, successive links being pivoted

25 together at their ends and forming an expansive toggle jointed system, guiding blocks supported on the central pivots of said links and provided with central apertures for said rod, means to selectively lock said rod with one of said guiding blocks, means to support one end of said system, and means to impart a reciprocating movement to the free portion of said system.

4. In a pumping mechanism, the combination with a pump plunger, a casing pipe, a rod extending from said plunger through the top of said pipe, a plurality of ring shaped links pivoted together at their middle portions, successive links being pivoted

40 together at their ends so as to form an expansive toggle jointed system, guiding blocks supported inside of said links on pivots connecting middle portions of said links and provided with central apertures for

45 said rod, clamps for said rod adapted to cooperate with said guiding blocks, flexible carriers on both sides of said rod, means to selectively connect said flexible carriers with one of the joints of said system, and means

to impart a reciprocating movement to said 50 flexible carriers.

5. In a pumping mechanism, the combination with a pump plunger, a casing pipe, a rod extending from said plunger through the top of said pipe, a plurality of links 55 pivoted together at their middle portions, successive links being pivoted together so as to form an expansive system, guiding blocks supported between said links and provided with apertures for said rod, means to support one end of said system, clamps adapted to selectively connect said rod with one of said guiding blocks, flexible carriers extending on both sides of said rod, means to selectively connect said flexible carriers with 60 one of the joints of said system, means to support the upper ends of said carriers, means to impart a reciprocating movement to said carriers, and means to equalize the tension on said flexible carriers on both 65 sides of said rod.

6. In a pumping mechanism, the combination with a pump plunger, a casing pipe, a rod extending from said plunger through the top of said pipe, a plurality of links 75 pivoted together at their middle portions, successive links being pivoted together thereby forming an expansive toggle jointed system, guiding blocks supported between said links and provided with apertures for said rod, means to support one end of said system, means to selectively connect said rod with one of said guiding blocks, flexible carriers extending on both sides of 80 said rod, means to selectively connect said carriers with joints of said system, a rotatively mounted rocking arm, means to impart a reciprocating movement to said arm, sheaves for said carriers on the end of said arm, and an equalizing sheave on top of said 85 arm and between said other sheaves, said flexible carrier being joined together at the periphery of said equalizing sheave.

Signed at New York, in the county of New York and State of New York, February 95
